UNITED STATES PATENT OFFICE.

WILLIAM NEWCOMB, OF JOHNSONVILLE, NEW YORK.

FIRE-ARM.

SPECIFICATION forming part of Letters Patent No. 308,513, dated November 25, 1884.

Application filed August 4, 1884. (No model.)

To all whom it may concern:

Be it known that I, WILLIAM NEWCOMB, a citizen of the United States, residing at Johnsonville, in the county of Rensselaer and State of New York, have invented new and useful Improvements in Fire-Arms, of which the following is a specification.

This invention has for its object to provide a novel and efficient fire-arm having two or more barrels, two firing-pins or nipples, and a hammer common to both firing-pins or nipples.

The invention consists in the construction and combination of devices hereinafter described and claimed, reference being had to the accompanying drawings, in which—

Figure 1 represents a sectional side view of the fire-arm. Fig. 2 is a plan or top view of the same. Fig. 3 is a perspective view of the striking-slide detached. Fig. 4 is a horizontal section of the trigger and the arm for lifting the striking-slide.

Similar letters indicate corresponding parts.

In these drawings, the letter A designates the stock. B is the breech-block. C D are the side barrels, and E is the middle barrel. These three barrels are fastened together by any suitable means, such as usually employed for fastening together the two barrels of double-barreled guns, and they are attached to the breech-block by well-known means so that they can be tilted up to expose their breech ends for the reception of the cartridges. These parts, however, form no part of my invention, and it is therefore not necessary to give a detailed description of the same. On the sides of the stock are two hammers, F G. The hammer F acts upon the firing-pin e of the side barrel, C, while the hammer G is so situated that when it comes down without meeting any obstruction it will strike the firing-pin d of the side barrel, D. The outer end of the firing-pin e of the middle barrel is situated in close proximity to the firing-pin d, and it extends through the breech-block in an oblique direction, as indicated in dotted lines in Figs. 1 and 2.

In order to bring the firing-pin e into the range of the hammer G, I have applied the striking-slide H. This striking-slide is placed into a recess, f, formed in the stock, and it is

provided at or near the middle of its length with a knuckle, g, Figs. 1 and 3, which bears against the rear surface of the breech-block B. Near its lower end said slide is provided with a short arm, h, Fig. 3, the upper surface of which is slightly inclined, Fig. 1, and exposed to the action of a spring, I, which is situated in a recess, J, in the side of the breech-block. This spring has a tendency to force the striking-slide downward, and also to throw the lower end thereof inward against the rear surface of the breech-block. On this lower end is formed a sharp-edged spur, i, and if the slide is moved up to the position shown in full lines in Fig. 1 the spring I throws this arm into a recess, j, formed in the rear surface of the breech-block. At the same time the head k of the slide is thrown back and brought in such a position that it is situated in the range of the hammer G, and also opposite to the outer end of the firing-pin e of the middle barrel, E. When the hammer G comes down, it strikes the head k and drives the same forward, so as to force the firing-pin e inward, while at the same time the slide forms a guard whereby the hammer is prevented from coming in contact with the firing-pin d of the barrel D. When the hammer G drives the head k of the slide H forward, the spur i is thrown out of gear with the recess j, and the slide, being free to follow the action of the spring I, is depressed to the position shown in dotted lines in Fig. 1, and if the hammer is cocked, the slide, having assumed this last-named position, leaves the hammer free to strike the firing-pin d of the side barrel, D.

In order to prevent the slide following the action of the spring I prematurely, a shoulder, l, is formed on the rear surface of the breech-block, and when the hammer strikes the head of the slide, so as to drive the firing-pin e forward, said slide, being free to follow the action of the spring I, sinks down a sufficient distance to prevent the spur i from entering the recess j. If the hammer is then cocked, the head of the slide is thrown back by the action of the spring I, so as to clear the shoulder l, and then the slide is depressed to the position shown in dotted lines in Fig. 1.

For the purpose of raising the slide to the position shown in full lines in Fig. 1, I use

an arm, K, which swings loosely on the pivot m of the trigger L, and a pin, o, secured therein, Figs. 1 and 8, rests against the edge n of the pin of this trigger. When the trigger is 5 pressed forward in the direction of the arrow marked near it in Fig. 1, the front end of the arm K forces the slide up until its spur i catches in the recess j. If desired, however, the slide may be so constructed that a portion of 10 it extends out through the bottom of the recess f in the stock, so that it can be forced up by pressing with the finger against this extension. If desired, both firing-pins d e may be placed outside of the range of the hammer, and in this 15 case the slide H must be so constructed that the same when moved up will enable the hammer to act upon the firing-pin e, and when it is moved down it will enable the hammer to act upon the firing-pin d.

20 It must be remarked that my invention can also be applied to muzzle-loaders, in which case the hammer serves to explode a percussion-cap placed upon nipples, which take the places of the firing-pins shown in the drawings.

25 I am aware that hammers have heretofore been provided with movable attachments to enable them to act on two different firing-pins or nipples, and I do not claim as my invention 30 a double-barreled gun in which one and the same hammer can be adjusted to act first upon the firing-pin or nipple of one, and then upon the firing-pin or nipple of the other barrel.

What I claim as new, and desire to secure by 35 Letters Patent, is—

1. The combination, with two barrels, a single hammer, and two firing-pins or nipples, of the vertically-moving slide H, having a knuckle on which it can rock, and arranged 40 between the hammer and the firing-pins or nipples, substantially as described.

2. The combination, with two barrels and two firing-pins or nipples, of the slide H, pro-

vided at or adjacent to the center of its length with a knuckle on which it can rock when 45 struck by the hammer, said slide having a head, k, to act on one of the firing-pins or nipples and at the same time constitute a guard to prevent the hammer from striking the other firing-pin or nipple, substantially as described. 50

3. The combination, substantially as hereinbefore described, with two barrels and a single hammer, of two firing-pins or nipples, one for each barrel, the slide H, situated between the hammers and the two firing-pins or nipples, and the arm K, actuated by the trigger L, and serving to raise the slide H. 55

4. The combination, substantially as hereinbefore described, with two barrels and a single hammer, of two firing-pins or nipples, one for each barrel, the slide H, situated between the hammer and the two firing-pins or nipples, the knuckle g, on which the slide rocks, the spur i, and recess j, the spring I acting on the 60 slide and having a tendency to depress the same, and means, substantially such as herein described, for raising the slide. 65

5. The combination, substantially as hereinbefore described, with two barrels and a single hammer, of two firing-pins or nipples, one for each barrel, the slide H, situated between the hammer and the two firing-pins or nipples, the knuckle g, on which the slide rocks, the spur i, and recess j, the spring I acting on the 70 slide, and having a tendency to depress the same, the shoulder l, and means, substantially such as herein described, for raising the slide. 75

In testimony whereof I have hereunto set my hand and seal in the presence of two subscribing witnesses.
